UNITED STATES PATENT OFFICE.

GUSTAVE GALLE, OF LAWRENCE, MASSACHUSETTS.

SHUTTLE CHECK.

Application filed March 19, 1928. Serial No. 262,974.

The present invention relates to shuttle checks for looms and has for its principal object to provide a device of this character adapted to engage the picker stick in friction gripping relation whereby to check the shuttle as the same is thrown into the shuttle box.

A further object of the invention is to provide means for releasing the shuttle check 10 from engagement with the picker stick to permit the return stroke thereof, said releasing action being controlled by a releasing rod disposed in a position for actuation by the crank arm of the loom.

15 A still further object of the invention is to provide a pair of yieldably mounted check shoes arranged in friction gripping relation with the opposite sides of the picker stick of the loom at the period of operation 20 of the loom when the shuttle is thrown into the shuttle box thereof and including means for adjusting the shoes in spaced relation with respect to each other and in alignment with the path of travel of said picker stick.

25 An additional object is to provide a device of this character of a simple and practical construction, is strong and durable, efficient and reliable in performance, relatively inexpensive to manufacture, and install in 30 operative position and otherwise well adapted to the purposes for which the same is intended.

Other objects and advantages reside in the 35 special construction, combination and arrangement of the various elements forming the invention as more fully hereinafter described and claimed, reference being had to the accompanying drawings forming part hereof, wherein like numerals refer to like 40 parts throughout, and in which:

In the drawings:

Figure 1 is a perspective view of the shuttle end of the loom showing the shuttle check comprising my invention in operative position 45 with respect thereto,

Figure 2 is a top plan view of the shuttle check, and

Figure 3 is a longitudinal sectional view therethrough.

50 Referring now to the drawing in detail, the invention comprises a shuttle check of a substantially elongated oval shaped formation and constructed of a U-shaped section 5 of rigid material at one end of the shuttle check, and with the end of said U-shaped section closed by an end section 6 formed of rela-

tively resilient material and preferably constructed of a plurality of layers of raw hide or similar material as clearly shown in Figure 3 of the drawings.

60 The area within the sections 5 and 6 is sufficiently large to permit the normal movement of the picker stick 7 of a loom of conventional construction as shown generally at 8 in Figure 1 of the drawings and embodies 65 a shuttle box 9, within which the upper end of the picker stick is disposed for operative connection with the shuttle of the loom, said loom also including the usual crank arm 10, associated in the movement thereof in a pre- 70 determined manner with the movement of the picker stick 7.

75 Between the side members of the section of the shuttle check 5 and extending longitudinally thereof in spaced relation is a pair of check shoes 11 having their opposed faces provided with a layer of friction material 12, one end of each of said shoes being freely mounted upon a bolt 13 extending transversely between the sides of the rigid section 5 80 and at a position thereon adjacent the closed end of said section, said bolt having a pair of coil springs 14 arranged thereon and disposed between the side of the section 5 and one of the shoes 11 whereby to yieldably 85 urge said shoes toward each other.

90 A spacing member 15 is interposed between the shoes 11, at the end thereof provided with the bolt 13, said spacing member being of a U-shaped formation as clearly illustrated in Figure 3 of the drawing with one end disposed between the shoes 11 and its opposite end disposed against the inner face of the end 16 of the section 5.

95 The portion of the spacing member 15 disposed against the end 16 is formed with a longitudinally extended slotted opening 17 within which a bolt 18 is adjustably fitted, with one end of the bolt inserted through a transversely disposed slotted opening 19 formed in the end 16 of the section 5, the outer end of the bolt carrying a nut 20 whereby to secure the parts in adjusted position with respect to each other.

100 From this construction it will be understood that the spacing member 15 may be adjusted transversely with respect to the sides of the section 5 of the shuttle check so that the check shoes 11 may be evenly spaced with respect to the path of movement of the 110 picker stick for engaging the opposite edges thereof.

Each of the check shoes 11 carries a laterally extending stud 21 which extends outwardly through an opening in the adjacent side of the section 5 each of said studs having a coil spring 22 arranged thereon and interposed between the shoe and the side of said sections for yieldably urging the ends of the shoe remote from the bolt 13 in a direction toward each other.

10 The outer ends of each of the studs 21 may carry suitable tension adjusting means for the spring, which may be in the form of a nut 23 threaded on the outer end of the stud or the like.

15 One of the brake shoes 11 is also provided with a laterally extending pin 24 extending through an opening in the side of the section 5 adjacent thereto, the outer end of said pin being provided with a collar 25 secured there-
20 to by means of a set screw 26. The collar 25 is spaced sufficiently from the outer face of the side of the section 5 so as to permit one end of a releasing rod 27 to be interposed between the collar and the side of the section 5, said releasing rod being arranged in the form of a crank with its intermediate section rotatably supported in brackets 28 attached to the loom frame and with its end remote from the pin 24 disposed substantially at right angles to the intermediate section of the rod as shown at 29 and operatively engaged by a pin 30 adjustably carried in a bracket 31 mounted along the upper edge of the crank arm 10 of the loom.

35 Provision is also made for the longitudinal adjustment of the sections 5 and 6 of the shuttle check by means of a longitudinally extending slotted opening 32 formed in one end of the section 6 through which a bolt 33 is inserted for attaching to the adjacent end of the section 5, the adjustment of the slotted end of the section 6 thus permitting an adjustment between the respective ends of the check.

40 It will be noted from an inspection of Figure 2 of the drawings that the ends of the shoes 11 remote from the spacing member 15 are arranged at a diverging angle with respect to each other and normally spaced apart a distance slightly greater than the width of the picker stick. The opposite ends of the shoes 11 are spaced apart a distance slightly less than the width of the picker stick so that the picker stick may freely enter the diverging end of the shoes until the opposite sides of the picker stick engage the inner faces of the shoe whereupon the movement of the picker stick will be checked and the same will furthermore be engaged in friction gripping relation by reason of the friction material 12 and through the action of the respective springs 14 and 22.

45 With the shuttle check arranged in a position with respect to the loom as shown in Figure 1 of the drawings, it will be appar-

ent to those skilled in the operation of looms of this character that the movement of the picker stick, during its actuation by the inward stroke of the shuttle, will be checked by the check shoes 11 and retained thereby until the shuttle is further actuated for its return movement. Consequently the inward movement of the shuttle will also be checked by this checking of the picker stick.

50 This return movement of the shuttle and picker stick coincide with the vertical movement of the crank arm 10 of the loom in a predetermined manner and as the crank arm 10 is actuated the releasing rod 27 accordingly moves the pin 24 outwardly so as to release the picker stick from engagement with the check tube 11. The throw of the picker stick toward the section 6 of the shuttle check is then permitted, the resiliency of the material from which the section 6 is constructed permitting the striking of the picker stick therein so as to check the movement thereof without causing injury to the same, and also prevent the picker stick from striking other parts.

55 It is obvious that my invention is susceptible to various changes and modifications in construction without departing from the spirit of the invention or the scope of the appended claims, and I accordingly claim all such forms of the device to which I am entitled.

Having thus described my invention, what I claim as new is:

1. In combination, a loom having a picker stick with a shuttle and crank arms operatively associated therewith, and check means for the shuttle arranged for engaging the picker stick whereby to check the movement of shuttle thereof in one direction and releasing means for the check means operable through said crank arm.

2. In combination, a loom having a picker stick with a shuttle and crank arms operatively associated therewith, and check means for the shuttle arranged for engaging the picker stick whereby to check the movement of shuttle thereof in one direction and releasing means for the check means operable through said crank arm, said check means comprising a pair of spaced check shoes adapted for frictionally engaging the opposite side of the picker stick.

3. In combination, a loom having a picker stick with a shuttle and crank arms operatively associated therewith, and check means for the shuttle arranged for engaging the picker stick whereby to check the movement of the shuttle thereof in one direction and releasing means for the check means operable through said crank arm, said check means comprising a pair of spaced check shoes adapted for frictionally engaging the opposite side of the picker stick, and spring means associated with each of said check shoes arranged for

yieldably urging the same in engagement with said picker stick.

4. In combination, a loom having a picker stick with the shuttle and crank arm operatively associated therewith and check means for the shuttle arranged for engaging the picker stick whereby to check the movement of each thereof in one direction and release the means for the check means operable to 10 said crank arm, said check means comprising a pair of spaced apart check shoes arranged adjacent each side of the path of movement of said picker stick and adapted for frictionally engaging the opposite sides thereof and 15 means for adjusting said shoes in a direction transversely with respect to the path of movement of the picker stick.

5. In combination, a loom having a picker stick with a shuttle and crank arm operatively associated therewith and check means for the shuttle arranged for engaging the picker stick whereby to check the movement of each thereof in one direction and releasing means for the check means operable to said crank 20 arm, said check means comprising a pair of spaced apart check shoes disposed adjacent the path of movement of the picker stick and adapted for frictionally engaging the opposite sides thereof, means for adjusting said 25 shoes in a direction transversely with respect to said path of movement of the stick and said releasing means comprising a releasing rod rotatably mounted intermediate its ends 30

with one end thereof engaging one of said shoe for the releasing movement thereof with 35 respect to the picker stick and its opposite end engageable by said crank arm for the actuation of the releasing rod during a predetermined period of the movement of said arm.

6. In combination, a loom having a picker 40 stick with a shuttle and crank arm operatively associated therewith, and check means for the shuttle arranged for engaging the picker stick whereby to check the movement of each thereof in one direction and releasing means 45 for the check means operable through said crank arm, said check means comprising a pair of substantially U-shaped sections having their ends connected in continuous arrangement, one of said sections being constructed of substantially resilient material to 50 form a bumper for the picker stick during its movement in one direction, a pair of spaced apart check shoes carried by the other of said sections and enclosed in the path of movement of said picker stick for frictionally engaging the same upon the movement thereof in an opposite direction, a casing member disposed at one end of said arm, spring means 55 engaging said arm whereby to urge the same toward each other and means for adjusting 60 said arms transversely with respect to the path of movement of said picker stick.

In testimony whereof I affix my signature.

GUSTAVE GALLE.
